ARTIFICIAL STONE

John J. Vicenzi, Boston, Mass.

Application January 2, 1937, Serial No. 118,840

5 Claims. (Cl. 72—45)

My invention relates to artificial stone, and more especially to artificial stone such as is used within buildings for walls, ceilings, floors, partitions and the like.

5 The object of my invention is to provide an improved artificial stone of the character described which will be comparatively inexpensive and which will be light, strong, substantially soundproof and also waterproof.

10 To these ends I have provided, as a new article of manufacture, an artificial stone tile product having the features of construction and distinguishing characteristics set forth in the following description, the several features of the invention 15 being separately pointed out and defined in the claims at the close thereof.

In the accompanying drawing:—

Figure 1 is a top plan view of a tile embodying one form of my invention, and

20 Figure 2 is an edge view, partly in section, of the tile shown in Fig. 1.

Figure 3 illustrates an alternative construction. My new artificial stone is essentially embodied in a composite laminated tile structure comprising 25 at least one outer exposed layer 11 which may be plain cement, magnesite or the like, but which as shown, is preferably terrazzo, the latter being ornamental and susceptible of being highly polished upon its exposed side, and also comprising 30 an inner layer 12 of fiber-board such, for example, as the well known "Celotex".

In the drawings I have embodied my invention in a tile suitable for use upon a concrete or other base to form a floor or wall, a multiplicity of such 35 tiles being laid edge to edge to provide a light, durable and ornamental structure that is substantially soundproof.

This tile comprises a rectangular cement or concrete frame 18 having relatively perpendicular cross-bars 19 which divide its interior into four rectangular compartments. Each compartment is occupied by a laminated filling comprising a bottom layer 17 of metallic reinforcing material such as a wire fabric; a layer 16 of asphalt or the 40 like which may be applied when the tile is laid; a layer 12 of fiberboard; a layer 15 of asphalt or the like; a layer 13 of metallic reinforcing material such as a wire fabric, and a layer 21 consisting of a mixture of cement and particles of 45 expanded and baked clay which latter is a granular product now on the market and known commercially as "Haydite". It is used in lieu of sand with cement to produce concrete because of its light weight which is about one-half that of 50 cement or sand.

Over the top of the several laminated fillings within the frame 18, and over the top of the latter also if desired, is spread a thin layer of terrazzo 55 whose top side is ground smooth and polished.

In practice the finished tile may measure three feet by three feet with the bars of the frame made one and one-half inches wide as viewed in Fig. 1. Thus the layers 12 and 21 constitute the major portion of the tile and consequently the latter is desirably light in weight and substantially 10 soundproof.

This construction provides a very strong, durable, light and ornamental tile requiring merely a thin veneer-like surfacing of terrazzo which 15 consists of crushed stone and cement and is of itself comparatively expensive and heavy.

This tile is comparatively inexpensive, substantially waterproof, and sound-proof to a marked degree owing to the cushioning effect of 20 the fiberboard layer 12. Furthermore, when the outer layer 11 is made from terrazzo or the like, and particularly when the exposed face of said outer layer is polished, the structure is ornamentally attractive. It also has the advantage that 25 tiles of this kind can be produced as a new article of manufacture so that walls, partitions, floors and the like can be quickly installed within a building. If desired, both sides of the tile may 30 include outside layers 11 and 11a, of terrazzo or cement as shown in Fig. 3.

What I claim is:

1. As a new article of manufacture, an artificial stone tile product comprising a frame of hardened cement defining a chamber, and a laminated structure filling said chamber including an inner imperforate cushioning layer of fiberboard; a perforate metallic reinforcement embedded within said structure upon the outer side of said inner cushioning layer; an outer hard 35 layer of cement, and fastening means connecting said inner cushioning fiberboard layer with said metallic reinforcement layer.

2. As a new article of manufacture, an artificial stone tile product comprising a frame of hardened cement defining a chamber, and a laminated structure filling said chamber including an outer hard layer of cement; an inner imperforate cushioning layer of fiberboard; a perforate metallic reinforcement embedded within 40 said structure upon the outer side of said inner cushioning layer of fiberboard; a perforate metallic reinforcement upon the innermost side 45 of said cushioning layer of fiberboard, and fastening means extending through said cushioning 50 layer.

ing layer of fiberboard for connecting said two metallic reinforcements therewith.

3. As a new article of manufacture, an artificial stone tile product comprising a frame of hardened cement defining a chamber; a laminated structure filling said chamber including an outer hard layer of cement; an imperforate inner cushioning and insulating layer of fiberboard; a perforate metallic reinforcement embedded within said outer layer; a thin layer of terrazzo covering said frame and the outer layer of said laminated structure, and fastening means connecting said inner cushioning fiberboard layer with said metallic reinforcement layer.

4. As a new article of manufacture, a tile comprising an isogonal marginal cement frame consisting of a plurality of narrow side-bars; an imperforate cushioning layer of fiberboard within said frame whose edges are entirely surrounded by the latter; two layers of waterproof material covering the opposite faces of said fiberboard; a perforate metallic reinforcement layer embedded in the outermost one of said layers of waterproof material; means positively fastening said metallic reinforcement layer to

said cushioning layer of fiberboard, and a layer of cement directly covering said outermost layer of reinforcement material, the outer surface of said last mentioned cement layer being flush with the outer surface of said frame.

5. As a new article of manufacture, a tile comprising an isogonal marginal cement frame consisting of a plurality of narrow side-bars; an imperforate cushioning layer of fiberboard within said frame whose edges are entirely surrounded by the latter; two layers of waterproof material covering the opposite faces of said fiberboard; two perforate metallic reinforcement layers within said frame each embedded in one of said layers of waterproof material; means positively fastening said two metallic reinforcement layers together and to said cushioning layer of fiberboard; a layer of cement within said frame covering the outermost layer of reinforcement material whereof the outer surface is flush with the outer surface of said frame, and a relatively thin layer of ornamental terrazzo covering the outer surface of said layer of cement and also the contiguous outer surface of said frame.

JOHN J. VICENZI.
